UNITED STATES PATENT OFFICE.

JOHN D. LEMEX, OF TULSA, OKLAHOMA.

CASING-HEAD APPLIANCE FOR OIL WELLS.

Application filed June 24, 1927. Serial No. 201,150.

This invention relates to a combined tubing hanger and slip operating means, and more particularly to an oil well appliance of the character specified designed to be applied 5 to a casing head secured to the upper end of a well casing and employed in conjunction therewith in the operation of pulling or running in the tubing used in oil and gas wells.

Among the objects of the present invention are, to provide a new and improved tubing hanger; to provide a new and improved combination tubing hanger, spider and slips; to provide a simple and efficient tubing hanger that may be readily applied to 15 the casing head and a previously inserted string or tubing without withdrawing the tubing from the casing or well, or breaking out or unscrewing any joints; and to provide new and improved labor saving means 20 associated with the hanger for positioning and removing the hanger slips.

Further additional objects and advantages of the present invention will be pointed out or become apparent from a consideration of 25 an operative embodiment as hereinafter described and as shown by the accompanying drawings.

In the drawings, which illustrate an application of my invention:

30 Fig. 1 is a plan view of a combined tubing hanger and slip operating means embodying my invention;

Fig. 2, a vertical sectional view, the section being taken on line II—II of Fig. 1, 35 looking in the direction of the arrows, the tubing being shown by dotted lines;

Fig. 3, a part elevational and a part sectional view, the section being taken on line III—III of Fig. 1;

40 Fig. 4, a top plan view of the hanger structure; and

Fig. 5, a horizontal sectional view taken on line V—V of Fig. 3.

Referring to the drawings, 5 designates 45 a hollow casing head designed to be attached to a section of a casing 6, said head 5 being provided with the usual outlet passages 7 and 8. In addition to the said passages 7 and 8, the head is formed with an annular 50 recess 9 adapted to receive a tubing hanger, indicated generally by the numeral 10. 11 designates threaded bolts for securing the tubing hanger 10 to the casing head.

The tubing hanger structure constitutes 55 an important and characteristic feature of my invention and, as shown, it includes a

body portion 12 having a centrally disposed tapered slip receiving bore 13 and a detachable or removable block member 14, the latter being designed to be received in an opening 15 formed in the body. Block 14 is designed to be entered vertically into the said opening, and may be removed from the body by sliding it vertically from the opening. Said block 14 is formed with shoulders 16 60 adapted to engage and cooperate with shoulders 17 formed in the body 12.

Body 12 is cut away, as shown at 18, and is also provided with registering openings 19 and 19^a, said openings 19 and 19^a being designed to register with an opening 20 formed in the block 14. These openings are adapted to receive a retaining bolt 21 for locking the block 14 in the hanger body. 22 designates an adjustable nut interiorly threaded at 23 65 to engage a threaded portion 24 of the bolt 21, said nut 22 being provided with aligned openings 22^a to receive a tool, not shown, employed for turning the nut.

It will be noted that the opening 15 is of 70 sufficient size to receive the tubing 25 and that the opening constitutes, when the block 14 is removed, a radially extending leading-in slot for the tubing, thus enabling the hanger to be applied to the string of tubing 75 that has been previously positioned in the casing and casing-head without the necessity of first raising the tubing and then lowering it through the bore of the hanger, as has heretofore been necessary.

Secured to the upper face of the tubing hanger by means of cap screw bolts 26, or other suitable means, and projecting upwardly and outwardly therefrom, is a plate-like support member 27. Member 27 is designed to pivotally support means operable from the exterior of the tubing hanger for positioning slips in and removing them from the tapered bore 13 of the body portion 12 of the hanger. The outer and upper end of the support 27 is thickened and formed with an upstanding apertured lug 28 forming a bearing for a shaft or a headed hinge bolt 29 loosely journaled therein.

Pivots connected with the shaft 29, I 105 provide a pair of operating lever members 31, said members 31, as shown, being tubular and formed at their secured ends with a slightly bent portion 32, said bent portion having an opening 33 through which the shaft 29 loosely extends. By bending the ends, as shown at 32, and providing the se-

curing lug 28 a slight V-shaped space 34 is provided at each end of the said bearing whereby the ends of the levers are permitted to have a slight inward and outward movement on shaft 29 to facilitate the operation of removing the slips from and placing them in the tapered bore of the hanger.

In the drawings, I have shown only two tubing engaging slips 35, but more than two slips may be employed and, if desired, the slips may be connected in pairs. Each slip 35 is serrated and is formed with a neck or handle portion 36 having an opening 37 therein designed to receive an end of a connecting member 38 depending from the said operating levers 31.

The slip connecting members, as illustrated, comprise link members 38 each formed with bent end portions 39 having their ends threaded as at 40, to engage a retaining nut 41. One threaded end portion 39 is adapted to be entered in the opening 37 of a slip and the other in an opening 42 of a lever 31.

It will be noted that the oil well appliance herein described comprises a construction that may be carried from well to well in an oil field, and readily positioned on casing heads and applied thereto even in cases where the tubing has been previously passed through the casing head and projects upwardly therefrom. Further, it also comprises a construction permitting the tubing hanger part to remain on a casing head while permitting the slip operating means to be detached therefrom and applied to another tubing hanger.

What I claim is:

1. In an oil well appliance of the character described, a tubing hanger having a tapered bore, a slip removably mounted in the bore, means detachably connected to the upper end of the tubing hanger for moving the

slip into and out of operative position, said means including a support member extending upwardly and outwardly from the upper end of the tubing hanger, a bent operating lever pivotally and shiftably connected to the support member, and a depending slip connecting member carried by the lever and connected to the slip. 45 50

2. In an oil well appliance of the character described, a tubing hanger having a tapered bore, slips removably mounted in the bore, means detachably connected to the upper end of the tubing hanger for moving the slips into and out of operative position, said means including a support member extending upwardly and outwardly from the upper end of the tubing hanger, an apertured lug on the outer end of the support member, a pivot pin passed through said lug, a pair of operating levers each pivotally connected to the upper and outer end of the support member by the pivot pin, said levers each having a bent end portion adjacent said lug whereby the ends may be shifted relatively to the lug, and depending slip engaging means carried by the said levers and connected to the slips. 55 60 65

3. In an oil well appliance of the character described, the combination with a tubing hanger having a slip receiving bore, of slip moving means detachably mounted on the hanger for moving slips into and out of operative position in the bore including a detachable support, a pair of levers having bent end portions pivotally and shiftably mounted at the outer end of the support, a pivot pin carried by the support upon which the levers are mounted, and loosely connected slip-engaging links depending from the levers, and connected to the slips. 70 75 80

In testimony whereof I affix my signature.

JOHN D. LEMEX.
